UNITED STATES PATENT OFFICE.

INGEMAR RYSTEDT, OF DAYTON, OHIO.

SPARK-PLUG.

1,371,058.

Specification of Letters Patent.

Patented Mar. 8, 1921.

Application filed June 4, 1917. Serial No. 172,710.

To all whom it may concern:

Be it known that I, INGEMAR RYSTEDT, citizen of the United States, residing at Dayton, in the county of Montgomery and State 5 of Ohio, have invented certain new and useful Improvements in Spark-Plugs, of which the following is a specification.

My invention relates to explosive engines and more particularly to ignition or spark 10 plugs therefor. The object of the invention is to improve the structure as well as the means and mode of operation of such devices, whereby they will not only be cheapened in construction, but will be more efficient 15 in use, protected against breakage, compression-tight and unlikely to get out of repair.

A further object of the invention is to provide an improved insulating core of heat 20 resistant material which will readily withstand extreme variation of temperature without crazing or cracking and to further provide means for ventilating the interior of the spark plug to facilitate the disbursement 25 of heat.

With the above primary and other incidental objects in view as will more fully appear in the specification, the invention consists of the features of construction, the 30 parts and combination thereof, and the mode of operation, or their equivalents, as herein-after described and set forth in the claim.

Referring to the drawings, Figure 1 is a side elevation of the assembled spark plug. 35 Fig. 2 is a longitudinal sectional view thereof. Fig. 3 is a longitudinal sectional view of a modification of the construction shown in Fig. 2. Fig. 4 is a detail view illustrating the method of attaching the spark point to 40 the central or insulated electrode.

Like parts are indicated by similar characters of reference throughout the several views.

In the drawings, 1 is the main bushing or 45 head having the hexagonal or polygonal collar 2, a screw threaded projecting stem 3 terminating in an oval or dome end 4 and on its upper side having a screw threaded boss 5. This main bushing is provided with 50 a central straight or cylindrical bore for the insulating core. Adjacent to the extremity of the bushing stem 2 or the inner end of said head or bushing the interior bore is provided with an interior groove or recess 7 55 forming a cement pocket as hereinafter de-

scribed. Inserted within the central bore of the bushing or head 1 is an insulating core 8 composed of quartz or fused silica, shaped and proportioned to accurately fit the interior of the bushing or bore. With the present method of manufacture, such quartz or fused silica cores cannot be accurately manufactured to provide a gas-tight joint between the core and the bushing. To overcome the difficulty and provide a compression-tight 60 joint, the exterior of the silica or quartz core 8 is generously coated with heat resistant cement of the porcelain cement type such as are now commonly in use. The annular groove or cement pocket 7 within the bore 65 of the bushing is also filled with such cement or sealing material which by its adherence with the quartz or silica core and with the metal bushing, firmly and securely unites the said parts together to form a compression 70 tight joint. While the film of cement surrounding the core 8 has been shown in the drawing as of appreciable thickness, it will be understood that with an accurately proportioned core this film of cement will be 75 extremely thin. While the cement film serves to firmly unite the quartz or silica core 8 with the walls of the bore of said bushing 1, the primary purpose of the cement is to fill any hollows or uneven or 80 non-uniform surfaces of the core 8, filling such depressions or surface markings to a uniform degree coincident with the walls of the bore of said bushing. Heat resistant cements of the porcelain type especially prepared and adapted for uniting various materials with metal, are to be had under various trade or proprietary names. Such cements unite not only with the metal but with the 85 quartz or silica, forming with the latter a 90 substantially homogeneous mass. The union of the body of cement within the pocket or annular groove 7 of the bushing with the inserted quartz or silica core provides an interlocking bead or collar upon said core 95 interengaged with the bushing in such a manner as to securely hold the core in position.

The quartz or fused silica of which the core 8 is manufactured possesses remarkable 100 heat resistant properties and a low coefficient of expansion which renders it particularly desirable for spark plug purposes. The coefficient of expansion of this material is so extremely small, being approximately one- 105

seventeenth that of glass, that it is enabled to withstand rapid changes of extreme degrees of temperature, without danger of breaking. It is likewise acid and chemical proof, resisting both acid and alkaline action at the ordinary temperature to which it is subjected in spark plug service. As an electrical insulator, quartz or fused silica is much superior to porcelain, mica, glass and similar materials commonly used in spark plugs and has been given an extremely high rating in comparison with these materials by the United States Bureau of Standards. This material is, however, extremely refractory and has a tendency when subjected to high temperature for a long period to become brittle. The present plug is designed to overcome this objectionable feature by affording protection to the insulating core 8 throughout its entire length in such a manner that it cannot be subjected to such force as to cause breakage.

In forming the core 8 it is provided with a central passage or bore proportioned to agree as nearly as possible in diameter with that of an electrode 9 to be passed therethrough. The electrode 9 forms one terminal of the ignition circuit. It is provided at its lower end with a collar or head 10 which abuts upon the inner end of the core 8. In order that the electrode 9 may accurately fit the bore or passage of the core 8 it is generously coated with the same character of heat resistant cement, such as porcelain cement or other cement or sealing material of the same type and is then introduced within the passage or bore of the core where the coating of cement will securely unite with the core, forming a compression-tight joint. The outer end of the electrode 9 is screw threaded as at 11 to receive a binding nut 12. Screw threaded upon the boss 5 of the head or bushing 1 is a sleeve 13 having therein a plurality of orifices or openings 14. The outer end of the sleeve 13 is internally screw threaded to receive a plug or cap 15 of fiber, bakelite, rubber, composition or other insulating material which is provided with a central bore or pocket into which the end 50 of the insulating core 8 projects. The plug or cap 15 is also provided with a central passageway through which the extremity of the electrode 9 extends. The end of the core 8 is coated with the same cement or one of like nature before being inserted in the bore or pocket of the cap or plug 15 and the latter is then screwed into place within the sleeve 13 whereupon the union of said cement with the fiber or other cap or plug and with the core firmly unites said parts and prevents their disengagement. The plug or cap 15 does not extend within the sleeve 13 into contact with the end of the boss 5, but there is left intermediate the boss 5 and the plug or cap 15 an intermediate annular space 16

surrounding the core 8 with which the openings or orifices 14 communicate. This space provides a ventilating chamber through which air may readily circulate about the core 8 to dissipate the heat of said core. At 70 its inner or sparking end the electrode 9 is bifurcated as shown at 18, the fingers of such bifurcation being bent outward and in reverse directions whereby they approach the rounded end 4 of the bushing 1. In Fig. 2 75 these sparking points are shown integral with the electrode 9. In Figs. 3 and 4, however, the electrode 9 is shown as being bifurcated at its extremity as indicated at 19. The sparking points in this instance are 80 formed of wire bent upon itself to a W-shape as at 20, the middle bight of which is engaged within the bifurcation 19 of the electrode 9^a of Fig. 3. The sparking points are retained by clenching or staking the fingers of the bifurcation 19 about the middle bight of the spark point member.

The construction shown in Fig. 3 differs from that of Fig. 2 also, through the fact that the sleeve 13^a of Fig. 3 is formed integral with the main bushing 1 in lieu of being screw threaded upon the hub 5 as shown in Fig. 2. Likewise the insulating plug or cap 15^a of the construction shown in Fig. 3, instead of being screw threaded within the sleeve 13^a is merely inserted therein and the upper end of the sleeve is contracted or clamped upon the plug or cap by a swaging operation.

The construction of the sparking points 100 insures a sufficient arc or spark gap and by affording double spark points reduces the difficulties due to fouling to minimum. The sparking points being opposed to the rounded surface 4 of the plug are afforded a large 105 sparking surface which will not readily burn or pit. The core 8 of quartz or fused silica having high insulating properties and with the further advantage of physical resistance to high temperatures and temperature 110 changes with a much lower decrease of insulating value with increase of temperature than is afforded by other insulating media commonly in use, together with the protection afforded to said core through the 115 total inclosure thereof, provides a spark plug of high efficiency.

From the above description it will be apparent that there is thus provided a device of the character described, possessing the 120 particular features of advantage before enumerated as desirable but which obviously is susceptible of modification in its form, proportion, detail construction or arrangement of parts, without departing from the 125 principle involved or sacrificing any of its advantages.

While in order to comply with the statute, the invention has been described in language more or less specific as to certain structural 130

features, it is to be understood that the invention is not limited to any specific details, but that the means and construction herein described comprise but one mode of putting 5 the invention into effect, and the invention is therefore claimed broadly in any of its possible forms or modifications within the scope of the appended claim.

Having thus described my invention, I 10 claim:—

A spark plug comprising a main bushing having a substantially uniform bore, a tubular extension engaged with the bushing of greater internal diameter than the bore, a 15 head engaged with said tubular extension, a core of insulating material extending through

the bore of the bushing and the tubular extension and having a nonyielding thrust bearing against said head whereby longitudinal movement of the core under the influence of compression and explosion within 20 the engine cylinder is resisted by said head, the strain of such thrust being transmitted thence through the extension to the main bushing, and an electrode inclosed within 25 the core.

In testimony whereof, I have hereunto set my hand this 24th day of May A. D. 1917.

INGEMAR RYSTEDT.
